CARBON PAPER FOLDER

Filed July 28, 1951

FIG. 3

INVENTOR.
GEORGE R. STEELE.

BY
Harold E. Stonebraker,
his ATTORNEY.

UNITED STATES PATENT OFFICE

2,609,924

CARBON PAPER FOLDER

George R. Steele, Irondequoit, N. Y., assignor to
 Kee Lox Manufacturing Company, Rochester,
 N. Y., a corporation of New York

Application July 28, 1951, Serial No. 239,173

2 Claims. (Cl. 206—62)

1

This invention relates to a carbon paper folder adapted to contain a multiplicity of sheets of carbon paper and to be packed in a conventional cardboard box along with a number of other similar folders packed with carbon paper, and has for its purpose to afford a folder consisting of a folded single sheet of cardboard or heavy paper which completely covers and protects the sheets of carbon paper when closed and includes a cover portion that when unfolded or opened receives the carbon and record or copy sheets in alternate arrangement for manifolding and locates them for assembling in proper relationship so that the stack of carbon sheets and record sheets can be easily removed for placement in a typewriter.

More particularly the invention has for its object to afford a one-piece folder so constructed that when in folded relation, the carbon sheets are maintained between two flat parallel areas of the folder and when unfolded, the supporting portion and cover portion are separated by a carbon-sheet elevating portion that raises the carbon sheets at one end for conveniently removing them, while the opposite end of the cover portion is provided with a flap that when folded can assume a perpendicular position and enables readily positioning the record and carbon sheets in alined relationship.

A further purpose of the invention is to afford a carbon paper folder consisting of a single sheet of paper or cardboard operable in the manner described above, which can be manufactured at a minimum cost and packed in a conventional carbon paper box so that the individual folders can be removed and used by operators at different locations, each operator being enabled by the construction of the folder to readily position and assemble a series of carbon sheets and record sheets on the folder for manifolding.

To these and other ends, the invention consists in the construction and arrangement of parts that will appear clearly from the following description when read in conjunction with the accompanying drawings, the novel features being pointed out in the claims following the specification.

In the drawings:

Fig. 1 is a plan view of a folder constructed in accordance with the invention, showing the cover portion in folded relationship over the supporting portion and a multiplicity of carbon sheets, the uppermost carbon sheet appearing partially in dotted lines;

Fig. 2 is a rear elevation of the same;

2

Fig. 3 is a view in side elevation showing the position of the supporting and cover portions when unfolded for assembling record and carbon sheets, with some carbon paper sheets resting on the supporting portion elevated at one end, and a multiplicity of alternating record and carbon sheets arranged on the cover portion ready to be removed;

Fig. 4 is a perspective view showing the position of the parts when unfolded with carbon sheets on the supporting portion elevated at one end, and showing in dotted lines in position occupied by a record sheet when positioned on the cover portion, and

Fig. 5 is a plan view illustrative of a record sheet superposed on a carbon paper sheet, in their relative positions for manifold assembly.

The invention of this application is an improvement on the structure of Patent No. 2,361,698, October 31, 1944, which is restricted in its use to the box in which the carbon paper folders are packed. With applicant's structure, any number of carbon paper folders can be packed in a conventional cardboard carbon paper box, and each folder when removed from the box can be used in the desired manner to permit ready assembly of carbon and record sheets on the folder itself for manifolding. This permits distributing folders to operators at different locations and each operator with her folder can assemble carbon sheets and record sheets easily and in the shortest time. The prior patented structure requires a specially constructed box that is considerably more costly to manufacture than the conventional carbon paper box and the carbon sheets are packed in conventional plain folders. With such arrangement, the carbon and record sheets can be assembled for manifolding only in the box containing the folders, and each operator must have a box to perform the manifold assembling operation, thus making it impossible to distribute folders and permit each operator to assemble carbon and record sheets for manifolding with her folder. Applicant's structure enables each folder to be used independently of the box to effect manifold assembling in the desired fashion, and employs a much more economically constructed box.

Referring more particularly to the drawings in which like reference numerals refer to the same parts throughout the several views, the folder consists of an integral or one-piece sheet of heavy paper or light cardboard including a carbon-paper supporting portion 1 and a cover portion 2 while 3 designates an elevating portion

connected to the supporting portion 1 by a fold or crease 4 and to the cover portion 2 by a fold or crease 5.

Referring to Fig. 4, the folds or creases 4 and 5 respectively are such that the elevating portion 3 bends downwardly away from the supporting portion 1 and bends upwardly away from the cover portion 2 when the parts are unfolded, and when folded, the elevating or connecting portion 3 assumes a horizontal position in alignment with the supporting portion 1, as indicated in Fig. 2, and the cover portion 2 folds over on the connecting portion 3 and supporting portion 1 along the crease or fold 5, as indicated in Fig. 1.

The supporting portion 1 is provided with a flap 6 foldable along the line 7 from the horizontal position shown in Fig. 1 where it overlies the end of the cover portion to the vertical position illustrated in Fig. 3, while 8 designates a flap connected to the cover portion 2 and foldable along the crease or fold 9 from the horizontal position beneath the flap 6, as shown in Fig. 1, to the perpendicular position as illustrated in Fig. 4.

The structure of the folder and the relation of the creases or folds 4, 5, 7 and 9 are such that when the parts are unfolded as in Fig. 4, the flaps or walls 6 and 8 and the elevating portion 3 automatically assume the perpendicular positions illustrated in Figs. 3 and 4, and when the cover portion 2 is folded over on the supporting portion 1 to cover and protect the carbon sheets, the elevating or connecting portion 3 assumes a horizontal position in continuation of the supporting portion 1 and underlying the cover portion 2 folded thereon, see Fig. 2, the flap or wall 8 likewise assuming a horizontal position beneath the flap or wall 6 that folds thereover, and the folder when in this position encloses a multiplicity of sheets of carbon paper and is positionable in any conventional box.

Several such folders, each containing a number of carbon paper sheets, can be packed in a conventional cardboard box and removed individually for use at different locations, permitting each operator to conveniently arrange a series of record or copy sheets and carbon paper sheets for manifolding by opening the folder so that the parts assume the positions illustrated in Figs. 3 and 4. When in such position, a record or copy sheet 11 is first positioned on the cover portion 2 with one edge against the flap or wall 8. The uppermost carbon sheet is then removed from the pile of carbons and supporting portion 1 and positioned over the record sheet, with one edge against the positioning wall or flap 8. The topmost carbon sheet is readily engaged by the operator by reason of the raising of the carbon sheets at one end over the vertically disposed elevating portion 3, and any number of record sheets and carbon sheets can be alternately arranged in this fashion until the desired number are positioned for the manifolding operation, being then removed by the operator who grips them as an entirety through the notch 12 at one edge of the cover portion 2.

The carbon sheets are somewhat longer than the record sheets, see Figs. 3 and 5, affording a gripping portion 13 on the carbon sheet at one end and opposite corners of the carbon sheet are cut away as at 14 and 15, so that when the typing operation is completed, the carbon sheets are easily separated in a group from the record sheets by holding the record sheets at one corner

adjacent to the cut-away portions 15 of the carbon sheets, and gripping the carbon sheets by the extended gripping portions 13. When the carbon sheets are thus removed, they are repositioned on the supporting portion 1 for further use when needed. With this method of operation, the carbon sheets when repositioned on the supporting portion after use are in the reverse order from their original position so that in successive typing operations, different portions of the carbon sheets are subjected to wear, and thus there is assured a more even distribution of work on the carbon sheets and their operative life in this fashion is considerably increased, while still permitting the use of paper folders packed in a conventional cardboard box.

While the invention has been described with reference to the particular structure herein shown, it is not limited to the details disclosed, and this application is intended to cover such modifications and departures as may come within the purposes of the improvement and the scope of the following claims.

I claim:

1. A carbon paper folder comprising a carbon sheet elevating wall, a carbon sheet supporting portion having a length as great as the carbon sheets and foldably connected at one end to said elevating wall, said supporting portion being positionable in alignment with said elevating wall or at an angle of approximately 90° thereto, and a cover portion having a length as great as the carbon sheets and foldably connected to said elevating wall at one end, said cover portion being positionable at an angle of approximately 90° to said elevating wall or overlying and parallel to said elevating wall and supporting portion, said elevating wall being located between said supporting and cover portions and the folding of the supporting and cover portions in relation to the elevating wall being permitted by creases formed in the folder from mutually opposite directions whereby the supporting and cover portions have a normal swing of not more than 90° in opposite directions in relation to the elevating wall so that when the folder is open the elevating wall is in a vertical position and the supporting and cover portions extend in opposite directions from the top and bottom edges thereof respectively and when the folder is closed the supporting portion and elevating wall are aligned and the cover portion overlies the supporting portion and elevating wall and is parallel thereto.

2. A carbon paper folder comprising a carbon sheet elevating wall, a carbon sheet supporting portion having a length as great as the carbon sheets and foldably connected at one end to said elevating wall, a flap integral with and extending across one end of the supporting portion and foldable toward carbon sheets on the supporting portion, said supporting portion being positionable in alignment with said elevating wall or at an angle of approximately 90° thereto, and a cover portion having a length as great as the carbon sheets and foldably connected to said elevating wall at one end, a flap integral with and extending across one end of the cover portion and foldable toward sheets on the cover portion, said cover portion being positionable at an angle of approximately 90° to said elevating wall or overlying and parallel to said elevating wall and supporting portion, said elevating wall being located between said supporting and cover portions and the folding of the supporting and cover portions in relation to the elevating

wall being permitted by creases formed in the folder from mutually opposite directions whereby the supporting and cover portions have a normal swing of not more than 90° in opposite directions in relation to the elevating wall so that when the folder is opened the elevating wall is in a vertical position and the supporting and cover portions extend in opposite directions from the top and bottom edges thereof respectively and when the folder is closed the supporting portion and elevating wall are alined and the cover portion overlies the supporting portion and elevating wall and is parallel thereto.

GEORGE R. STEELE.
